UNITED STATES PATENT OFFICE.

HENRY A. ALTER, OF YONKERS, AND HERBERT J. WOLLNER, MORRIS SCHWARTZMAN,
AND BENJAMIN SCHWARTZMAN, OF NEW YORK, N. Y.

FUR-DRYING APPARATUS.

Application filed March 11, 1927. Serial No. 174,582.

This invention relates to improvements in fur drying apparatus.

The primary object of the invention resides in the provision of a device in which the skins or pelts to be dried are inserted and subjected to a moving column of atmospheric air which facilitates the quick and even drying of the same without fear of stiffening the skins.

Another object of the invention is to provide a fur drying device which includes a cabinet for removably receiving a pair of panels on which the skins to be dried are stretched and which panels are disposed in spaced converging relation to each other to provide a restricted enclosed conduit for the passage of a column of atmospheric air adapted to be blown therethrough, the skins or pelts being mounted on the inner faces of the panels and subjected to the blast of air.

A further object of the invention is the provision of a fur drying device in the form of a table or bench, in which a drying compartment is arranged and which receives a pair of removable boards on which the furs to be dried are mounted, the said boards now being used in the fur industry for receiving the furs or pelts to be stretched, thus making it unnecessary for a fur dealer to go to the expense of having separate boards for the stretching and drying operations.

A further object of the invention resides in a combination work table and fur drying apparatus which may be used by furriers when preparing the skins for drying and which are later inserted into the apparatus for drying purposes.

A still further object is to provide an apparatus of the kind above mentioned which is simple in construction, inexpensive of manufacture and highly efficient for the purposes intended.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of our improved fur drying apparatus.

Figure 2 is a vertical longitudinal section-al view therethrough.

Figure 3 is a vertical transverse sectional view on the line 3—3 of Figure 2.

Figure 4 is a fragmentary horizontal sectional view on the line 4—4 of Figure 2.

Referring more particularly to the drawings, the reference numeral 10 designates a table or work bench which includes a flat top 11 and supporting legs 12. Supported by the legs 12 in parallel spaced relation to the top 11 is a bottom wall 13, opposed side walls 14 and 15, and opposed end walls 16 and 17. These walls coact to provide an enclosed cabinet or compartment 18, access to which may be had through an opening normally closed by a swinging door 19 mounted on the side wall 14 and which door is of the drop type. The door may be held in a closed position by suitable turn buttons 20 during the fur drying operation presently to be described. An air entrance opening 21 is provided across the end wall 16 while an air outlet opening 22 extends across the end wall 17, the opening 21 being of a height greater than the height of the opening 22 for a purpose to be presently explained.

Extending inwardly from the end walls 16 and 17 and disposed on opposite sides of the openings provided therein, are spaced tracks 23 and 24 respectively for slidably receiving a pair of panels 25. The ends of the panels are received in the tracks by inserting the panels through the opening provided in the side wall 13 when the door 19 is swung down. The panels 25 align with the upper and lower walls of the openings 21 and 22 and coact with the side walls 14 and 15 for providing an enclosed conduit 26 between the entrance and outlet openings. The panels or boards 25 are now used by furriers for stretching the skins or pelts and are stretched on the boards and held thereon by nails or like fastening elements, after which stretching the panels may be inserted in the dryer and the skins disposed upon the adjacent faces of the panels where they are subjected to a blast of atmospheric air adapted to be passed through the conduit 26.

Mounted over the entrance opening 21 and supported by the end wall 16 is an air distributor 27 in which is arranged a plurality of angularly disposed baffle plates or walls 28 which deflect the air evenly to the entrance 21 from an air pipe 29. Atmospheric air is forced through the pipe and

conduit 26 by a blower 30 mounted in the air inlet pipe and which is of the usual well-known construction.

By varying the height of the inlet and outlet openings 21 and 22 and by having the tracks 23 and 24 on different levels, the panels 25 are supported in converging relation to each other so as to provide an enlarged air entrance and a restricted air outlet, which causes the air to back-up in the conduit to thoroughly dry the fur or skins supported by the removable panels 26. By reason of the size of the panels, any number of pelts may be dried in a single operation and after insertion into the dryer, the same may be left to dry without requiring a worker to be in attendance.

For facilitating the insertion and removal of the panels from the cabinet, the same may be provided with hand receiving recesses 31 in their inner faces adjacent the longitudinal side edges thereof.

From the foregoing description, it will be seen that we have provided a combination work table and fur drying apparatus, the table being used in preparing the furs for the drying operation, i. e., for mounting the skins upon the panels, after which the panels bearing the skins are inserted into the dryer as hereinbefore mentioned.

While we have described what we deem to be the most desirable embodiment of our invention, it is obvious that many of the details may be varied without in any way departing from the spirit of our invention, and we therefore do not limit ourselves to the exact details of construction herein set forth nor to anything less than the whole of our invention limited only by the appended claims.

What is claimed as new is:—

1. A fur drying apparatus comprising a cabinet having inlet and outlet openings respectively provided in opposed walls thereof, and spaced converging fur receiving panels removably supported within said cabinet between said inlet and outlet openings and co-acting with certain other opposed walls of said cabinet to provide an enclosed conduit between said inlet and outlet openings.

2. A fur drying apparatus comprising a cabinet having a door therein, and a pair of removable panels supported in converging spaced relation within said cabinet and adapted to have the furs to be dried mounted on their inner faces, said panels co-acting with certain opposed walls of said cabinet to provide an enclosed conduit therein.

3. A fur drying apparatus comprising a cabinet having a door therein, and a pair of removable panels supported in converging spaced relation within said cabinet and adapted to have the furs to be dried mount-

ed on their inner faces, said panels co-acting with certain opposed walls of said cabinet to provide an enclosed conduit therein, and means for passing a blast of atmospheric air through said conduit to subject the action of the same to the furs adapted to be mounted on said panels.

4. In a fur drying apparatus, the combination of a table having a cabinet disposed beneath the top thereof, a pair of panels having the furs to be dried mounted on the inner faces thereof, and means for removably supporting said panels within said cabinet in converging spaced relation with respect to each other.

5. In a fur drying apparatus, the combination of a table having a cabinet disposed beneath the top thereof, a pair of panels having the furs to be dried mounted on the inner faces thereof, and means for removably supporting said panels within said cabinet in converging spaced relation with respect to each other, to provide a conduit having an enlarged air inlet and a restricted air outlet, and means for forcing atmospheric air through said conduit from the inlet end to the outlet end thereof for subjecting the furs to the action of the same.

6. A fur drying apparatus comprising a cabinet having an air inlet opening in one of the end walls thereof and an air outlet opening in the opposed end wall, tracks provided on the inner faces of the opposed walls but disposed out of alignment with each other, and fur supporting panels insertible through one of the side walls and slidable on said tracks for forming a conduit converging from the inlet opening to the outlet opening.

7. A fur drying apparatus comprising an enclosed cabinet having an air inlet opening at one end thereof, and an air outlet opening in the opposed end wall, the outlet opening being of a height less than the height of said inlet opening, spaced tracks provided on the inside of said end walls, the tracks of the first end wall being spaced a greater distance apart than the tracks on the other end wall, one of the side walls having an opening extending the length thereof, a pair of fur supporting panels insertible through the last mentioned opening and slidable over the respective tracks for alignment with said inlet and outlet openings for forming a converging conduit therebetween, and a door for closing said last opening after the insertion of said panels.

In testimony whereof we hereby affix our signatures.

HENRY A. ALTER.
